UNITED STATES PATENT OFFICE.

ALLEN CAMPELL SANDERS, OF ERIE, PENNSYLVANIA.

ELLIPSOGRAPH.

Application filed May 25, 1925. Serial No. 32,879.

This invention relates to improvements in drawing instruments and it consists of the constructions, combinations and arrangements herein described and claimed.

5 An object of the invention is to provide a compass by means of which ellipses and ovals of various sizes and proportions can be drawn or inscribed in an expeditious and accurate manner.

10 Another object of the invention is to provide an ellipsograph which, having been adjusted to the two dimensions along the minor and major axes of the intended ellipse, can with one continuous turn be made to draw 15 such ellipse accurately.

Other objects and advantages will appear in the following specification, reference being had to the accompanying drawings, in which—

20 Figure 1 is a perspective view of the improved ellipsograph, illustrating the initial act of setting the pen at *a* along the minor axis of the intended ellipse.

Figure 2 is an elevation thereof.

25 Figure 3 is another elevation showing how the pivot leg may be leaned over so that the drawing pen may touch the paper.

Figure 4 is a detail section on the line 4—4 of Figure 3.

30 Figure 5 is a perspective view illustrating the second act in adjusting the ellipsograph along the major axis of the intended ellipse until the drawing pen touches the point *b*.

Figure 6 is a detail sectional view substantially on the line 6—6 of Figure 5.

35 Figure 7 is a detail sectional view of the improved pivot foot.

Figure 8 is a diagram illustrating various kinds of ellipses or ovals actually drawn by 40 the instrument.

The general appearance of the improved drawing instrument is that of an ordinary compass for drawing pencil or ink line circles, and true to its similarity with the ordinary compass the improved instrument has 45 pivot and drawing legs 1 and 2, so called because of their respective functions. The drawing pen 3 is removable from the drawing leg by means of the set screw 4, and is 50 replaceable by a pencil point or other appropriate instrument with which the desired inscription is to be made.

Unlike the ordinary compass the pivot leg 1 does not turn about its axis. It is provided with a foot 5 with three points 6 which are intended to pierce the drawing surface

to prevent the turning of the pivot leg as stated. It is upon this foot that the instrument can be either rocked or swayed sideways upon the points 6 and lengthwise upon the bearing furnished by the semi-circular edge 7 and the corresponding semi-circular recess 8 in the enlargement 9. The arrangement permits the free oscillation of the pivot leg without turning, the center line or axis 65 of the leg always pointing exactly to the center of the drawing area.

The pivot foot 5 is retained by means including a screw 10 (Fig. 7).

The upper end of the pivot leg 1 terminates in a head 11 which carries a pair of rollers 12. The axes 13 (Fig. 4) of the rollers extend at right angles to the axis of the screw 10. The turning plane of the rollers 12 is at right angles to the plane in which the pivot leg 1 is capable of swinging in respect to the pivot foot 5. The latter direction of swinging is from right to left in Figs. 1 and 2. A stem 14 is pivoted at 15 in the head 11. The stem passes through 80 a slot 16 in a disk 17 which is revoluble upon the rollers 12, and it is not until the disk 17 has been turned sufficiently to dispose the slot 16 parallel with the axes 13 of the rollers that the stem can be rocked or tilted 85 upon its pivot (Figs. 5 and 6).

The stem 14 passes through the central projection 18 of the handle yoke 19. The handle yoke is revoluble upon the stem, continuously when the instrument is in use to 90 draw an ellipse. But the stem 14 will rock upon its pivot 15 only in the event that it is adjusted out of coaxial alignment with the pivot leg 1 whereupon it partakes of a 95 rocking motion consonant with the revolution of the disk 17.

The revoluble disk 17 has a pair of diametrically opposite ears 20 into which pivots 21 are fastened by screw threads or otherwise. Screws are preferable because they permit 100 tightening. The yoke 22 of the drawing leg 2 is mounted upon the pivot screws 21. Washers 23 are interposed between the screw head, handle yoke and drawing yoke 22 on each side. The pivot screws provide a frictional mounting of the drawing yoke 22 upon the handle yoke 19, permitting independent adjustment of the drawing leg as when setting the drawing pen 3 to the lesser dimension of the intended ellipse as at the point *a* 110 in Figure 1. This particular adjustment is independent of all other functions.

A frictional mounting for the handle yoke 19 upon the ears 20 of the revoluble disk 17 is also afforded by the pivot screws 21 so that the adjustment of the handle yoke in respect to the disk will be held when the handle is bent back in setting the instrument for the greater dimension of the intended ellipse as when the drawing pen is made to touch the point *b* in Figure 5. The first adjustment is made of the drawing yoke in respect to the handle yoke, but the second adjustment is made of the handle yoke in respect to the revoluble disk.

A sleeve 24 constitutes that part of the handle which taken in the fingers of the operator to revolve the compass according to custom. The sleeve is tubular and fits upon a tubular collar 25 upon the stem 14. The extremity of the stem is threaded at 26 to carry a nut 27 by means of which the tension of a spring 28 may be regulated. The spring, being disposed between the collar 25 and nut 27 exerts pressure upon the revoluble disk 17 to keep it in firm contact with the rollers 12. Turning of the sleeve 24 causes turning of the yoke 19 by means of a suitable connection between the two, for example lugs 29 which fit in recesses 30.

In order to insure holding the relative adjustment of the handle and yoke 19 in respect to the revoluble disk 17 when drawing ellipses, the disk is provided with a semi-circular plate 31 against which a set screw 32 can be made to bear. The set screw is carried by an enlargement 33 on the underside of the yoke 19.

To use the instrument the points 6 of the pivot foot 5 are set upon the major axis C of the intended ellipse, the central point coinciding with the intersection of the minor axis D. The point pricks are indicated at 34 in Figure 8. With the finger and thumb the operator grasps the drawing leg 2 and pulls it in the direction of the minor axis until the pen point registers with the mark *a* of the intended ellipse (Fig. 1). The compass is now swung around 90° and upon grasping the handle sleeve the yoke 19 is bowed over (Fig. 5) until the pen point 3 touches the mark *b* on the major axis. The instrument is now set to draw the intended ellipse.

To draw the ellipse the draftsman may begin at the point *a* and swing the compass by twirling the handle sleeve 24 between the finger and thumb as with an ordinary compass, leaning the instrument toward the drawing point or pen 3 and keeping an even pressure thereof upon the drawing paper. The ellipse is drawn with a continuous motion, it being unnecessary to lift the drawing pen from the paper until the ellipse is completed. The ellipse 35 (Fig. 8) is an example. To draw an ellipse of the same width as the ellipse 35, but with a different

length, the drawing pen is swung in the direction of the major axis and the yoke 19 is bowed by means of the handle sleeve 24 until the pen point touches the desired dimension as at *e* (Fig. 8). The foregoing drawing operation is repeated, and the ellipse 36 is the result. Obviously the line may be either full or dotted.

The ellipse 37 is drawn in a manner identical with that of drawing the first two ellipses, but differs therefrom by being long and narrow. The instrument is capable of drawing even narrower ellipses, and when used with the stem 14 in line with the axis of the pivot leg 1 (or in the exact center of the revoluble disk 17) will draw perfect circles.

The operation may be briefly described so that the reader may visualize the working of the compass. It is readily seen that the pivot leg 1 is rendered stationary, so far as turning movement is concerned, by impressing the three points 6 into the paper. Any twirling or twisting of the handle 24 will turn the handle yoke 19, the two being connected and result in the revolution of the disk 17 upon the rollers 12 of the pivot leg. The drawing pen 3 is carried by the revoluble disk, and as long as the stem 14 remains coaxial with the pivot leg 1, the revolution of the disk 17 will result in the drawing of a circle by the pen point. The disk 17 then revolves in a plane at right angles to the axis of the pivot leg.

Upon bending back upon the handle as in making the adjustment for the dimension of the ellipse along the major axis (Figs. 5 and 6) the stem 14 (Figs. 4 and 6) is turned upon its pivot 15 so that it no longer assumes the coaxial relationship with the pivot leg 1. When the handle is now twirled to draw the ellipse there occurs a relative motion of the stem 14 and disk 17. The stem 14 rocks from side to side upon its pivot, the degree of rocking motion depending on the extent that it has been adjusted out of alignment with the pivot leg. The disk 17 instead of revolving in the former horizontal plane now partakes of an eccentric revoluble motion from front to rear of the pivot leg, the degree of eccentric motion of the disk being determined by the angularity of the stem 14, but in all cases the relative motions of the parts are symmetrical.

The action is best understood by keeping in mind that a twirling effort upon the handle 24 must be distributed to the parts directly connected to it. Such twirling effort will turn the stem 14, but by virtue of its angularity (Fig. 6) the twirling motion will be resolved in a side to side rocking motion of the stem upon the pivot 15. As long as the handle assumes the angularity in Figure 6 the revoluble disk will be found in the horizontal plane on top of the rollers 12. As soon as the handle has rocked into co-

axial alignment with the pivot leg 1 (due to the foregoing twirling motion) the disk 17 will be found in eccentric position on the other side of the pivot leg as shown in dotted lines in Figure 6, it being borne in mind that any adjusted relationship of the handle and yoke 19 with the revolute disk is preserved both by the frictional engagement at the pivots 21 and by the set screw 32. The resulting action is an eccentric or oscillating motion of the revolute disk upon the rollers 12 accompanied by a rocking back and forth of the handle sleeve 24. This motion accompanies the drawing of the ellipse for which the instrument has been adjusted.

The advantages may be briefly reviewed. The instrument performs as does an ordinary compass to produce a perfect circle of any diameter within the range of the instrument, without making any adjustment but supposing the handle stem 14 to be coaxial with the pivot leg 1, as already stated.

It performs as does an ordinary compass with two legs, one constituting the pivot, the other the drawing, cutting, marking or scratching implement. From the position assumed by the instrument in ordinary drawing, it can be said to draw an ellipse or oval of any proportions. The pivot foot 5 contains three points 6 which pierce the drawing paper and prevent the pivot leg 1 from turning as ordinarily. It is upon this foot that the instrument can be rocked sidewise either upon its points 6 or upon its semi-circular edge 7, allowing it to sway or oscillate without turning and always keeping the center line of the leg pointing exactly to the center of the drawing area.

It has been noted that the handle yoke is capable of adjustment in respect to the revolute disk 17 only when the part 16 has been turned around at right angles to the pivot 15 of the handle stem 14. It would be impossible to bend the handle in any direction when positioned as in Figure 1 because the sides of the slot prevent rocking upon the pivot in the direction of the major axis and the pivot 15 itself prevents rocking of the handle in the direction of the minor axis. The disk 17 provides a path on which rollers 12 travel.

In drawing a circle, ellipse or oval the pen point 3 remains in the proper drawing position in respect to the line that it is producing. The pen point is not pushed into an improper drawing position as is usually the case with other instruments for drawing ellipses or ovals.

The instrument need not be operated in an upright position but can be leaned in any manner as an ordinary compass. In fact it operates like an ordinary compass with the added advantage of being adjustable to draw an ellipse or oval. The instrument permits drawing of an elliptical figure by continu-

ously marking the line outside of the area covered by the instrument. Other instruments require drawing within themselves or permit drawing only part of an ellipse before they are required to be turned in an opposite or some other direction to complete the ellipse.

I claim:—

1. An instrument of the character described comprising a non-revolute pivot leg, a scribe carried thereby, means including a disk which is revolute upon the pivot leg, a pivot by which the stem is connected with the pivot leg whereby the stem is adjustable in respect to the disk and pivot leg, 75 said stem when coaxial with the pivot leg causing the disk to revolve in a plane at right angles to the axis of the leg but when tilted upon its pivot causes the disk to revolve with an oscillatory movement in respect to the pivot leg of a degree determined by the angularity of the stem, and means to connect the scribe to the disk so as to move the scribe in consonance with the combined motion of the stem and disk thereby inscribing an ellipse.

2. An instrument of the character described comprising a non-revolute pivot leg, a drawing leg having a scribe, means carrying the drawing leg and being revolute in a 95 plane at right angles to the axis of the pivot leg thereby to describe a circle, and means pivoted on said pivot leg and associated with said revolute means for rocking said revolute means in respect to said right angular plane thereby distorting the motion of the drawing leg about the pivot leg to describe an ellipse.

3. An instrument of the character described comprising a non-revolute pivot leg, 105 a drawing leg having a scribe, a disk carrying the drawing leg, and means having common frictional connection with said disk and drawing leg and freely pivotal connection with said pivot leg, said last means and said disk being adjustable relatively to each other to cause revolution of the disk in a horizontal plane when held at right angles to the pivot leg thereby causing the description of a circle or to revolve with an oscillating motion in respect to the pivot leg to a degree determined by the angularity of adjustment of said means in respect to the pivot leg thereby cause said drawing leg to describe an ellipse.

4. An instrument of the character described comprising a non-revolute pivot leg, a drawing leg having a scribe, a disk, and means pivotally associated both with the pivot leg and the disk and whereby the drawing leg is connected to the disk at one of said pivotal mountings, said means being adjustable in respect to the pivot leg at its other pivotal mounting thereby to cause an oscillating motion of the disk and a rocking 125

- motion of said means in respect to the pivot leg axis resulting in the description of an elliptical outline upon operation of the instrument.
5. An instrument of the character described comprising a non-revolute pivot leg, a drawing leg having a scribe and a yoke, a disk, a stem pivoted upon the pivot leg, a handle including a yoke which is revolute upon the stem, and a common, frictional pivotal connection between the drawing yoke, handle yoke and disk permitting a single adjustment of the drawing leg and yoke in respect to the handle yoke and disk to determine a measurement along the minor axis of an intended ellipse, and permitting a composite adjustment of the drawing and handle yoke in respect to the disk to determine a measurement along the major axis of the intended ellipse, the rocking of the stem upon its pivotal mounting being consonant with the last adjustment and determining the degree of oscillation of said disk upon revolution to make said ellipse.
25. An instrument of the character described comprising a non-revolute pivot leg, a drawing leg having a scribe and a yoke, a stem pivoted upon the pivot leg, a handle including a yoke journaled upon the stem, a disk, and pivots providing a common frictional connection between the drawing and handle yokes and the disk, said disk being in horizontal alignment with the stem pivot when the stem is coaxial with the pivot leg, thereby permitting uniform revolution of the disk in a plane at right angles to the pivot leg axis, but periodically departing from said alignment when the stem is adjusted upon its pivot at an angle to the pivot leg axis, thereby causing an oscillation of said disk in respect to the pivot leg during revolution.
7. An instrument of the character described comprising a pivot leg having a head, roller bearings on the head, a stem pivoted upon the head on an axis in line with but normal to the axis of said roller bearings, a drawing leg having a yoke, a handle including a yoke having a projection journaled upon the stem, a disk revolute upon the roller bearings and upon said stem having ears, pivots frictionally connecting said drawing and handle yokes to the ears, said handle yoke and stem being in alignment, and means to hold the disk in contact with said roller bearings including a nut adjustable upon the stem and a spring interposed between and exerting pressure against the nut and against the handle yoke.
8. An instrument of the character described comprising a non-revolute pivot leg, a disk, a scribe adapted to move about the axis of the pivot leg, means including a yoke and stem through which the scribe respectively has pivotal attachment with the disk, and a pivotal connection with said pivot leg and means to fix said adjustment including a plate carried by the disk and a screw associated with said yoke.
9. An instrument of the character described comprising a non-revolute pivot leg, a disk, a scribe connected to the disk so as to revolve therewith about the axis of the pivot leg, a handle yoke pivotally connected to the disk and by which revolution is imparted to the disk, a stem pivotally carried by the pivot leg upon which the handle yoke and disk are revolute, and a sleeve fitted upon the stem to be manipulated by the fingers of the operator, said sleeve being connected with the handle yoke by means of lugs and recesses.

ALLEN CAMPBELL SANDERS.
